C. W. KECKLER

TELEPHONE EXCHANGE SYSTEM

Filed Dec. 6, 1919

Inventor:
Charles W. Keckler.
by C. P. Soper Att'y.

UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 6, 1919. Serial No. 343,003.

To all whom it may concern:

Be it known that I, CHARLES W. KECKLER, a citizen of the United States, residing at Newark, in the county of Essex, State of New Jersey, have invented certain new and useful Improvements in Telephone-Exchange Systems, of which the following is a full, clear, concise, and exact description.

This invention relates to telephone exchange systems and more particularly to circuit arrangements at a manual private branch exchange where such an exchange is employed in connection with a main exchange of the common battery type.

An object of the invention is to provide improved signaling means for such systems, and to avoid the tying up of trunks extending between the private branch exchange and the distant exchange in cases of slow disconnect on the part of the operator.

Another object of the invention is to provide for instantaneous recall on the part of the subscriber at the private branch exchange or the distant office.

A further object of the invention is to prevent ringing current from falsely signaling the connected subscriber at the private branch exchange in cases of a second call from the distant office for the private branch exchange prior to disconnection by the operator.

In the present embodiment of the invention the circuit arrangements are such that the subscriber at the private branch exchange controls the release of a trunk leading to the distant office.

More specifically restoration of the receiver to the switchhook of the subscriber at the private branch exchange, after completion of conversation with a subscriber at the distant office, opens the line loop thereby causing a supervisory lamp to be actuated and the automatic switches at a distant office to be released. Restoration of the receiver also causes a switching relay in the trunk circuit at the private branch exchange to operate thereby connecting the line signal to the trunk and opening up the trunk conductors, which enables the operator to again be signaled over said trunk and prevents ringing current from passing to the con-

nected station in case of a slow disconnect.

A further feature is the provision of means whereby, prior to disconnecting by the operator, the subscriber at the private branch exchange may either signal the operator indicating that a connection with another station of the private branch exchange is desired or he may without the aid of the operator call a subscriber at the distant office, in the latter case a supervisory relay being actuated at the private branch exchange thus indicating to the operator thereat that the line and trunk connected thereto are busy.

For a more complete understanding of this invention reference should be had to the following description and to the accompanying drawing which illustrates one embodiment thereof. While the invention is shown in connection with an automatic exchange, obviously it could be employed with a manual common battery exchange.

There is shown in the drawing a telephone line A terminating in an automatic exchange. By means of an impulse sender S and automatic switching apparatus, such as a line finder F, selector L and connector C, diagrammatically indicated, the subscriber A may select a trunk such as T extending from the automatic exchange to the manual private branch exchange. The apparatus shown to the left of the dotted line O—O is located at the automatic exchange and that to the right thereof at the manual exchange. At the manual exchange, a signaling means, a switching relay and a jack in which the trunk terminates are provided. By means of the link circuit B the calling line A may be extended to any station such as D terminating in a jack at the private branch exchange.

The nature of this invention is such that it is believed that a clear understanding thereof will be obtained from a description of the operation of the system shown in the drawing, and it will be so described.

It will be assumed that a subscriber at substation A in the automatic exchange desires a connection with a subscriber D terminating in a manual exchange. The subscriber at substation A will therefore re-

move the receiver from the switchhook and then operate the sender S in the manner well known to extend his line to an idle trunk such as T leading to the manual exchange.

After an idle trunk has been found the side switch brushes 10, 11 of the connector C are moved to position 3 in the usual manner and ringing current is sent over the conductors 12, 13 of the trunk T to the manual exchange to actuate a signal 20 thereat, the path therefor being as follows: ground, third contact of side switch and its brush 10, conductor 12, outer left-hand armature and back contact of relay 21, left-hand winding of relay 22, condenser 23, conductor 13, side switch brush 11 and its third contact, winding of relay 24, and armature and front contact of relay 25, (which is energized in position 3 of the side switch brushes) to source of ringing current 26. Relay 22, upon energization establishes a locking circuit for itself including its right-hand winding, front contact and armature and the back contact and inner left-hand armature of relay 21 and also completes a circuit for the line signal 20 from battery, lamp 20, front contact and armature of relay 22 and back contact and inner left-hand armature of relay 21 to ground.

In response to the signal, the operator inserts the plug 28 of the link circuit B into jack 29 of the trunk circuit T. Relay 21 of the trunk circuit T and relay 30 of the link circuit B are thereupon energized over a circuit from grounded battery, winding of relay 21, sleeves of jack 29 and plug 28, left-hand normal contact of relay 31 and winding of relay 30 to ground. Relay 21 in energizing disconnects the ringing relay 22 from the trunk circuit and interrupts the circuit for the lamp 20 at its left-hand armatures and at its right-hand armatures connects the trunk circuit through to the link circuit B. Relay 30 of the link circuit B at its inner left-hand armature and front contact completes a bridging circuit, including the left-hand inner armature and back contact of relay 44 and the windings 32 and 33 of a retardation coil, across the talking conductors of the cord circuit thereby causing ringing relay 24 in the connector circuit C to energize to trip the machine ringing and move the side switch brushes of the connector into position 4 in the manner well known.

The operator then actuates the listening key 35 thus connecting her telephone set (not shown) in circuit so that she may converse with the calling subscriber, and having ascertained that station D is desired, the operator inserts calling plug 40 of the link circuit into jack 41, in which the line leading to station D terminates. Supervisory lamp 42 lights and the line cut-off relay 43

is energized over a circuit extending from grounded battery, lamp 42, back contact and right-hand armature of relay 44, back contact and armature of supervisory relay 45, sleeves of plug 40 and jack 41 and winding of relay 43 to ground. The operator will then actuate ringing key 46 of the link circuit B to signal station D in the usual manner.

Upon response of the called subscriber, a path for the talking current for station D may be traced as follows: ground, left-hand winding of relay 5 of the connector C, side switch brush 10 in its fourth position, conductor 12, front contact and outer right-hand armature of relay 21, tip of jack 29 and of plug 28, upper normal contacts of ringing key 50, right-hand normal contacts of dialing key 51, upper normal contacts of ringing key 46, tip of plug 40, tip of jack 41, through the substation loop, ring of jack 41, ring of plug 40, lower normal contacts of ringing key 46, through inductive winding of relay 45 and the non inductive winding 52 thereof front contact and right-hand armature of relay 30 in parallel, left-hand normal contacts of dialing key 51, lower normal contacts of ringing key 50, ring of plug 28, ring of jack 29, right-hand inner armature and front contact of relay 21, conductor 13, side switch brush 11 in its fourth position, and right-hand winding of relay 5 of the connector C to grounded battery. Sufficient current flows through supervisory relay 45 to cause its energization although up until the time that relay 45 is energized, the retardation coil windings are bridged across the link circuit. Relay 45 attracts its armature and in so doing causes the supervisory lamp 42 to be extinguished and the holding bridge across the talking conductors of the link circuit B to be disabled. Relay 44, which interrupts the holding bridge at its inner left-hand armature and back contact, is energized over the following paths: grounded battery, outer left-hand armature and front contact of relay 30, winding of relay 44, front contact and armature of relay 45, sleeve of plug 40, sleeve of jack 41, and winding of relay 43 to ground. Relay 44 is held locked up through its outer left-hand armature and front contact and the normal contact of listening key 35 through resistance coil 27 to ground.

At the conclusion of conversation subscriber D restores the receiver to the switchhook, thus opening up the loop for relay 5 of the connector switch C, which will cause the restoration of the switches in the automatic exchange in the manner well known. Trunk circuit T may then be selected by another connector causing trunk signal 20 to light even though the plug 28 is not removed from jack 29 immediately, as in the

case of a slow disconnect, in a manner hereinafter described.

Supervisory relay 45 is deenergized upon the restoration of the receiver of station D to its switchhook, thereby causing energization of relay 31 over a path extending from grounded battery, winding of relay 31, front contact and right-hand armature of relay 44, back contact and armature of supervisory relay 45, sleeve of plug 40, sleeve of jack 41, and winding of relay 43 to ground. Relay 31, upon energization, establishes at its right-hand armature and front contact a circuit for supervisory lamp 42 causing it to light to indicate to the operator that conversation is completed. At the left-hand armature and normal contact of relay 31, the circuit for relay 21 is interrupted, thus opening up the talking conductors of the trunk T, and again bridging the ringing relay 22 across the trunk.

In case another call comes in over the trunk from the automatic exchange, before the operator has disconnected, ringing relay 22 will again be energized causing the line signal 20 to light. Ringing current will be prevented from passing through to the station D since the talking conductors of the trunk are open at the contacts of relay 21. When relay 31 was energized a circuit for relay 30 was maintained through grounded battery, resistance 60, and the left alternate contacts of relay 31, which are of the make-before-break type.

Assuming that a second call has arrived over the trunk circuit T, relay 22 will be energized as heretofore described and the trunk lamp 20 will light. The operator observing the signal actuates listening key 35 and in so doing interrupts at its normal contact the locking circuit for relay 44. Relay 44, upon deenergization, interrupts at its right-hand armature and contact, the circuit for relay 31 and at its inner left-hand armature and back contact restores the bridge across the talking conductors of link circuit B. Relay 31 in deenergizing again completes a circuit at its left-hand armature and normal contacts for relay 21, which, upon energization, disconnects ringing relay 22 and signal 20 from the trunk circuit B, and reestablishes the continuity of the talking conductors of the trunk circuit. The bridge across the link circuit B trips the machine ringing as before and causes the side switch brushes to move from position 3 to position 4, thus enabling the operator to converse with the calling subscriber. In case substation D is again desired, the operator actuates the ringing key 46 to signal station D, or in case some other station is desired, plug 40 is removed from jack 41 and inserted in the jack in which the desired line terminates. Upon completion of conversation supervisory lamp 42 lights, as be-

fore described, whereupon the operator removes the plugs from their associated jacks and all relays are restored to normal.

Assume that substation D desires to make a call or gain the attention of the operator prior to disconnection. The supervisory lamp 42 of the cord circuit may be flashed in response to actuations of the switchhook at station D. Removal of the receiver at station D prior to disconnection, causes energization of supervisory relay 45 over the following path: ground, resistance 16 of the trunk circuit T, tip of jack 29 and of plug 28, upper normal contacts of ringing key 50, right-hand normal contacts of dialing key 51, upper normal contacts of ringing key 46, tip of plug 40 and of jack 41 over the loop of station D, ring of jack 41 and of plug 40, lower normal contacts of ringing key 46, inductive winding of supervisory relay 45 and non-inductive winding 52 thereof, and right-hand armature and front contact of relay 30 in parallel, left-hand normal contacts of dialing key 51, lower normal contacts of ringing key 50, ring of plug 28 and of jack 29, inner right-hand armature and back contact of relay 21, and resistance 15 to grounded battery. Attraction of the armature of relay 45 interrupts the circuit for supervisory lamp 42. The operator noting the supervisory signal actuates listening key 35 and converses with station D, and in case another station at the manual exchange is desired, plug 28 will be removed from jack 29 and inserted in the jack to which the desired line is connected.

Supposing on the other hand that prior to disconnection station D desires to dial a subscriber at the automatic exchange. It will be remembered that prior to removal of plugs 28 and 40 from their associated jacks, and after the subscriber at station D has hung up, relays 21 and 45 are deenergized and relays 30, 44 and 31 are energized. Removal of the receiver at station D from the switchhook energizes supervisory relay 45, which attracts its armature, thereby interrupting at its back contact the circuit for lamp 42 causing it to be extinguished and indicating to the operator that the cord circuit is in use. Attraction of the armature of relay 45 also interrupted at the back contact thereof, the circuit for relay 31 causing it to deenergize. Deenergization of relay 31 re-establishes at its left-hand armature and normal contact, the circuit for relay 21, causing the latter to energize, thus extending the line of station D over the trunk circuit T to the automatic exchange, where the trunk terminating at the connector C may be multiplied to the line or trunk finder schematically represented on the drawing by the rectangle X. The subscriber at station D may now actuate his dial E to select the number desired in the manner well-known.

With each interruption in the line circuit of station D, relay 45 will deenergize and at its armature and back contact close a circuit for relay 31. This relay is of the slow-to-operate type, however, and will not follow the interruptions in the line circuit. To indicate that relay 31 is of the slow-to-operate type, arrows pointing in the direction in which the armatures slowly move are shown 10 on the drawing.

Upon completion of conversation, restoration to the switchhook of the receiver at station D will open the line circuit, cause deenergization of supervisory relay 45 and the 15 lighting of lamp 42. Armature of relay 45 in retracting again completes the circuit for relay 31, which, upon energizing, interrupts the circuit for relay 21, thereby again connecting the alternating current bridge across 20 the trunk and interrupting the continuity of the trunk conductors. The operator, noting that the supervisory signal 42 is lit, will remove the plugs from their associated jacks, and all relays will be restored to normal. 25

A calling dial 61 is provided for the cord circuit by means of which the operator may select for the calling subscriber D, a line terminating in the automatic exchange. Resistances 62 and 63 connected to battery and ground, respectively, supply current to the line of subscriber D when dialing key 51 is actuated, so that the subscriber may still control the supervisory signal. Since such 30 arrangements are well-known and this forms no part of the present invention, a description of such an operation is deemed unnecessary. 35

What is claimed is:

40 1. In a telephone exchange system, a manual switchboard, a trunk line including a pair of normally discontinuous talking conductors terminating thereat, an alternating current bridge normally connected to said talking conductors, a subscriber's line terminating at said switchboard, a link circuit for connecting said trunk line to said subscriber's line, a relay in said trunk circuit adapted upon energization to interrupt said 45 alternating current bridge and establish the continuity of said talking conductors, means under the control of the operator for energizing said relay, and means under the control of the subscriber for deenergizing said 50 relay.

55 2. In a telephone exchange system, an automatic telephone exchange, a calling subscriber's line terminating thereat, a manual telephone exchange, a called subscriber's line terminating thereat, means including automatic switches and a trunk circuit for extending a connection from said calling to said called line, a link circuit at said manual exchange for extending said calling to said 60 called line, signaling means associated with 65

said trunk circuit, means under the control of the operator for disconnecting and reconnecting said signaling means to said trunk circuit, and means controlled by the called subscriber independently of the operator for disconnecting and reconnecting said signaling means. 70

3. In a telephone exchange system, a trunk circuit including a pair of normally discontinuous talking conductors, signaling means normally connected to said trunk circuit, a switching relay in said trunk circuit adapted upon energization to establish the continuity of the talking conductors of said trunk circuit and to disconnect said signaling means, and upon deenergization to restore said trunk and said signaling means to normal condition, a subscriber's line, a link circuit for connecting said trunk circuit with said subscriber's line and means controlled by the subscriber for energizing or deenergizing said switching relay. 80

4. In a telephone exchange system, a manual exchange, a subscriber's line terminating at said manual exchange, a trunk circuit extending to an automatic exchange terminating at said manual exchange, a link circuit at said manual exchange for completing a connection received from said automatic exchange for a subscriber at said manual exchange, and means controlled by the subscriber at said manual exchange for rendering the trunk selectable immediately upon completion of conversation. 90

5. In combination with a trunk circuit and a cord circuit for extending a call from a subscriber at an automatic exchange to a subscriber at a manual exchange, means whereby when the called subscriber at the manual exchange hangs up after completion 100 of conversation, the trunk circuit is available for a recall or a second call over said trunk. 105

6. In a telephone exchange system, an automatic exchange, a calling subscriber's line terminating thereat, a manual exchange, a called subscriber's line terminating thereat, means including a trunk line for extending said calling line to said manual exchange, a link circuit at said manual exchange for extending said trunk line to said called line, means under the control of the called subscriber for releasing the switches at said automatic exchange, and means whereby the called subscriber may 110 immediately after having released said switches, initiate a call over said link circuit and said trunk circuit for an automatic subscriber without the aid of the operator. 115

7. In a telephone exchange system, an automatic exchange, a calling subscriber's line terminating thereat, a manual exchange, a called subscriber's line terminating thereat, means including a trunk circuit for extending a call from said calling subscriber 120 125 130

- to said manual exchange, a link circuit at 25
said manual exchange for extending said
trunk circuit to said called line, means under
the control of the called subscriber for re-
5 leasing the switches at said automatic ex-
change, means for enabling the called sub-
scriber to initiate a call for a subscriber at
said automatic exchange immediately after
having released the switches, and supervisory
10 means in the link circuit actuated in re-
sponse to the initiation of said call for indi-
cating to the operator that said link circuit
is in use.
8. In a telephone exchange system, an
15 automatic telephone exchange, a calling sub-
scriber's line terminating thereat, a manual
telephone exchange, a called subscriber's line
terminating thereat, a trunk circuit extending
between the two exchanges, switching
20 apparatus controlling the continuity of the
trunk line and a line signaling device asso-
ciated with said trunk circuit at the manual
exchange, the signaling device responding to
a call initiated by the calling subscriber, a
link circuit at the manual exchange for con- 25
necting said trunk to the line of the called
subscriber, means for disabling the signal-
ing device and for actuating the switching
apparatus to receive the incoming call upon
the connection of the link circuit with the 30
trunk circuit, means controlled by the called
subscriber for restoring said switching ap-
paratus and the signaling device to normal
association with said trunk circuit, said
35 signaling device being in readiness to be
again actuated upon a second incom-
ing call over the trunk circuit from the
automatic exchange, and operator-con-
trolled means for again disabling the sig- 40
naling device and for actuating the switch-
ing apparatus for the receiving of a second
call while maintaining the original connec-
tion of said link circuit with said trunk
circuit.

In witness whereof, I hereunto subscribe 45
my name this 3rd day of December A. D.,
1919.

CHARLES W. KECKLER.
